UNITED STATES PATENT OFFICE

2,067,235

MERCURY SWITCH RELAY

Uno C. Hedin, Elkhart, Ind., assignor to The
Adlake Company, a corporation of Illinois

Application August 17, 1935, Serial No. 36,704

11 Claims. (CL 200—112)

The efficiency of any electro-magnetic relay is to a large extent dependent upon the characteristics of the iron circuit associated with the switching element and its arrangement with respect to the switching element. It is a primary object of this invention to improve upon the iron circuits heretofore used with mercury switches of the type disclosed in Larson 1,967,247, issued July 24, 1934, and to reduce the power necessary for operating them.

Further objects and advantages will become apparent as the disclosure proceeds and the description is read in conjunction with the accompanying drawing, in which

Fig. 1 is a vertical, sectional view showing a preferred form of the invention;

Fig. 2 is an end elevational view of the relay;

Fig. 3 is a perspective view showing the component parts of the iron circuit, the parts being somewhat displaced for clarity of illustration; and

Fig. 4 is a plan of the relay.

The illustration and specific description of a preferred form of the invention are for the purpose of complying with section 4888 of the revised statutes, and the appended claims should not be construed as limited to the particular form shown and described unless required by the prior art.

The relay comprises a coil 10, an iron circuit generally designated 11, and a switching element 12, the latter taking the form of a mercury switch of the mercury displacement type. The details of the switch are unimportant here, and it will suffice to point out that the switch comprises a switch envelope 13 of boro-silicate glass, electrodes 14 and 15 sealed through the base of the envelope (the latter electrode being surrounded for a portion of its length by a sleeve 16 of insulating material), a mercury fill 17, and a displacer generally designated 18 comprising an inner tube 19 of ceramic material over which a sleeve 20 of magnetic material is telescoped. Guide washers 21 of hardened steel fit against the ends of the armature sleeve 20 and are held in place by springs 22 which frictionally engage the walls of the inner tube 19.

It will be understood that when the displacer 18 is in the position shown in Fig. 1, the mercury fill within the switch envelope closes the circuit between the electrodes 14 and 15, but when the displacer is raised by energization of the coil 10, the mercury level falls below the bared end 23 of the central electrode 15 and opens the circuit 55 through the switch.

The lower portion of the switch is encased within a base comprising a bakelite sleeve 24 which is held in place by a suitable sealing compound 25. The base serves the purpose not only of protecting the electrode seals from damage but also prevents short circuiting of the switch by accidental crossing of the exposed ends of the electrodes and their leads.

The iron circuit 11 associated with the switching element comprises a laminated yoke 27 made of Allegheny transformer electrical sheet iron, the ends 28 and 29 of the yoke extending above and below the relay coil.

Attached to the ends of the yoke 27 are pole blocks generally designated 30 and 31, each of which is provided with a square notch 32 adapted to interfit with the squared ends 33 of the yoke 27. The pole blocks are secured to the yoke by screws and nuts 34 and 35, as best shown in Fig. 4.

The pole blocks are preferably made of Sve-electrical iron because of its purity and low reluctance. The blocks have vertically aligned apertures 36 which are coaxial with the core opening 37 of the coil and each block is counterbored from its inner face, as indicated at 38 to receive pole sleeves 39 and 40, respectively, also of high grade electrical iron. The inside diameter of the pole sleeves is the same as the diameter of the apertures 36 so that the mercury switch within the pole sleeves may be vertically adjusted for position without being fouled by the pole pieces.

A brass sleeve 41 separates the pole sleeves 39 and 40 and has an inside diameter slightly less than the outside diameter of the switch envelope 13 so that when the switch envelope is in place, the brass sleeve frictionally engages the envelope and holds it in adjusted position.

The pole blocks 30 and 31 are preferably cold drawn and after they have been machined, they are annealed at 1750° F. for approximately five hours. They are then finished with Udylite.

The pole sleeves 39 and 40 and the component laminations of the yoke 27 are likewise annealed and finished with Udylite.

Both pole blocks are vertically split as indicated at 42 between the vertical apertures 36 and the notches 32. As a result, the portions of the pole blocks which are secured to the yoke 27 act as jaw arms in gripping the yoke. This is quite important as it is necessary to have intimate contact between the yoke and pole blocks if efficient operation of the relay is to be obtained.

It has heretofore been the practice to have the pole sleeves directly connected to the ends of the

yoke, as shown for example in Larson Patent 1,967,951. It is a rule that after any machining on parts of an iron circuit, there must be subsequent annealing, and since each lamination of the yoke must be separately plated after annealing, it is obvious that there is considerable complication in having to mill the ends of the yoke, then anneal, then plate the laminations separately, and finally assemble the laminations in proper order to make up the yoke.

The iron circuit of this invention, however, has the advantage that no machining of the yoke is necessary so that the individual laminations may be annealed and plated and then assembled with the rest of the iron circuit.

The relay of this invention also has the distinct advantage that the switch is mounted within the coil where the magnetic flux is strongest, and where minimum power is required for operating the switch. Furthermore, the air gap between the top of the armature sleeve 20 and the lower end of the top pole sleeve 39 is located at the center of the coil where the concentration of flux is at its maximum. By locating the air gap at this point, the top of the switch envelope lies within the top pole block 30 with no portion extending above, thus affording protection against breakage of the glass envelope. The bared end of the electrode 15 is located just below the coil 10 and when the inner ceramic sleeve 19 of the displacer is made of glass, it is desirable to provide a window opening 43 in the bottom pole block and lower pole sleeve so that the operation of the switch parts may be observed.

The pole blocks, being of substantial cross section and extending an appreciable distance beyond the switch envelope, evenly distribute the flux around the switch envelope, thus preventing horizontal components of flux from acting upon the armature sleeve 20 and increasing the friction of the displacer within the switch envelope. The pole blocks 30 and 31 may be rounded at their ends for greater efficiency if desired.

The vertical splits 42 in the top and bottom pole blocks prevent eddy currents from travelling around the switch envelope when the relay is being operated on alternating current and thus enable the relay to be used efficiently with this type of current.

It is obvious that the invention may be variously modified within the scope of the appended claims.

I claim:—

1. In a mercury switch relay, a relay coil having a core opening, a mercury switch mounted within the opening and comprising a switch envelope, a mercury fill, spaced electrodes in the envelope, and a magnetically responsive displacer for shifting the mercury level to change the condition of the electrical circuit through the electrodes, and an iron circuit associated with the coil and the switch having portions extending above and below the coil, top and bottom pole blocks of substantial cross section attached to said portions and projecting over the core opening of the coil, and pole sleeves in the core opening attached to the pole blocks and separated from each other by an air gap located approximately at the center of the coil.

2. In a mercury switch relay, a relay coil having a core opening, a mercury switch mounted within the opening and comprising a switch envelope, a mercury fill, spaced electrodes in the envelope, and a magnetically responsive displac-

er for shifting the mercury level to change the condition of the electrical circuit through the electrodes, and an iron circuit associated with the coil and the switch having portions extending above and below the coil, top and bottom pole blocks of substantial cross section attached to said portions and projecting over the core opening of the coil, and pole sleeves in the core opening attached to the pole blocks and separated from each other by an air gap located approximately at the center of the coil, said pole blocks being recessed to receive the pole sleeves.

3. In a mercury switch relay, a relay coil having a core opening, a mercury switch mounted within the opening and comprising a switch envelope, a mercury fill, spaced electrodes in the envelope, and a magnetically responsive displacer for shifting the mercury level to change the condition of the electrical circuit through the electrodes, and an iron circuit associated with the coil and the switch having portions extending above and below the coil, top and bottom pole blocks attached to said portions and projecting over the core opening of the coil, and pole sleeves in the core opening attached to the pole blocks and separated from each other by an air gap located approximately at the center of the coil, said pole blocks having aligned apertures that are counterbored for receiving the pole sleeves.

4. In a mercury switch relay, a relay coil having a core opening, a mercury switch mounted within the opening and comprising a switch envelope, a mercury fill, spaced electrodes in the envelope, and a magnetically responsive displacer for shifting the mercury level to change the condition of the electrical circuit through the electrodes, and an iron circuit associated with the coil and the switch having portions extending above and below the coil, top and bottom pole blocks attached to said portions and projecting over the core opening of the coil, and pole sleeves in the core opening attached to the pole blocks and separated from each other by an air gap located approximately at the center of the coil, said pole blocks having aligned apertures that are counterbored for receiving the pole sleeves.

5. In a mercury switch relay, a mercury switch mounted within the opening and comprising a switch envelope, a mercury fill, spaced electrodes in the envelope, and a magnetically responsive displacer for shifting the mercury level to change the condition of the electrical circuit through the electrodes, and an iron circuit associated with the coil and the switch having portions extending above and below the coil, top and bottom pole blocks attached to said portions and projecting over the core opening of the coil, and pole sleeves in the core opening attached to the pole blocks and separated from each other by an air gap located approximately at the center of the coil, said pole blocks having aligned apertures that are counterbored for receiving the pole sleeves, and a brass sleeve separating the pole sleeves and frictionally engaging the walls of the switch envelope for supporting the latter within the core opening.

6. In a mercury switch relay, a relay coil having a core opening, a mercury switch mounted within the opening and comprising a switch envelope, a mercury fill, spaced electrodes in the envelope, and a magnetically responsive displacer for shifting the mercury level to change the condition of the electrical circuit through the electrodes, and an iron circuit associated with the

coil and the switch having portions extending above and below the coil, top and bottom pole blocks attached to said portions and projecting over the core opening of the coil, and pole sleeves in the core opening attached to the pole blocks and separated from each other by an air gap located approximately at the center of the coil, and an opening in the bottom pole block permitting observation of the switch parts.

7. In a mercury switch relay, a relay coil having a core opening, a mercury switch mounted within the opening and comprising a switch envelope, a mercury fill, spaced electrodes in the envelope, and a magnetically responsive displacer for shifting the mercury level to change the condition of the electrical circuit through the electrodes, and an iron circuit associated with the coil and the switch having portions extending above and below the coil; top and bottom pole blocks attached to said portions and projecting over the core opening of the coil, said pole blocks being split horizontally and formed with jaws adapted to engage said projecting portions of the iron circuit.

8. In a mercury switch relay, a relay coil having a core opening, a mercury switch mounted within the opening and comprising a switch envelope; a mercury fill, spaced electrodes in the envelope, and a magnetically responsive displacer for shifting the mercury level to change the condition of the electrical circuit through the electrodes, and an iron circuit associated with the coil and the switch having portions extending above and below the coil, top and bottom pole blocks attached to said portions and projecting over the core opening of the coil, each of said pole blocks having a circular aperture and a vertical split extending from one face of the block to the aperture.

9. In a mercury switch relay of the class described, a switch element, a relay coil and an iron circuit associated with the element and coil, said iron circuit including a pole block having a square notch in one face, a circular opening through the block, and a vertical split connecting the opening and the notch. 5

10. In a mercury switch relay of the class described, a switch element, a relay coil and an iron circuit associated with the element and coil, 10 said iron circuit including a pole block having a square notch in one face, a circular opening through the block, and a vertical split connecting the opening and the notch, said opening being counterbored for a portion of its length. 15

11. In a mercury switch relay, a relay coil having a core opening, a mercury switch mounted within the opening and comprising a switch envelope, a mercury fill, spaced electrodes in the envelope, and a magnetically responsive displacer for shifting the mercury level to change the condition of the electrical circuit through the electrodes, and an iron circuit associated with the coil and the switch having portions extending above and below the coil, top and bottom pole 25 blocks of substantial cross section attached to said portions and projecting over the core opening of the coil, and pole sleeves in the core opening associated with the pole blocks for fixing the position of the air gap between the pole blocks, 30 said pole blocks having aligned apertures adapted to receive the switch and having sufficient mass encircling the switch so that the tendency of the displacer to move laterally upon energization of the coil is substantially eliminated. 35
